UNITED STATES PATENT OFFICE

SIDNEY B. BLAISDELL, OF PHILADELPHIA, PENNSYLVANIA, ASSIGNOR TO FIDELITY MACHINE COMPANY, OF WILMINGTON, DELAWARE, A CORPORATION OF DELAWARE

BRAIDING MACHINE

Application filed April 28, 1927. Serial No. 187,301.

This invention relates to braiding machines, each of which, in common practice, is provided with a main platform over which the bobbins carrying the braiding threads are moved in a circuitous and intertwining path, suitable mechanism being provided under the platform for synchronously moving the plurality of bobbins. Each braiding machine is also provided with a take-up head and a take-off mechanism, which are positioned above the bobbin platform. Each machine is also equipped with a separate driving pulley, a control clutch, and a stop motion. Each braiding machine thus requires a definite amount of floor space, and a certain amount of aisle space to permit an operator to pass between the machines.

In factories employing a number of such machines, considerable space is wasted by the separate driving pulleys and the necessity of setting up line shafts to drive these individual machines. Also for each machine in operation a separate pulley must be provided on the line shaft and a separate driving belt also provided. Thus it will be seen that in addition to the valuable floor space wasted, there is considerable capital necessarily invested in equipment including pulleys, belts, etc.

The object of my invention is to consolidate a plurality of these individual machines, or units, into a single machine, but at the same time retain the independent utility features of each unit. According to the principles of my invention, a plurality of braiding units are mounted on a single frame and a single driving pulley is provided for the entire number of consolidated units, thus the units can be placed close together and thereby conserve the space otherwise wasted in accommodating the driving mechanisms of the several independent machines, also, but one driving pulley is required on the line shaft and one belt connects these pulleys, thus a saving in both equipment and in upkeep are accomplished. Obviously the line shaft may be replaced by an independent motor for each consolidated machine, if desired.

The structure constituting my invention is

clearly illustrated in the accompanying drawings, of which:

Fig. 1 is a front elevation of an apparatus embodying the principles of my invention;

Fig. 2 is a plan view, with the lower mechanism not shown;

Fig. 3 is a sectional plan view taken on the line 3—3 of Fig. 1, showing the lower mechanism;

Fig. 4 is an elevation of the drive end of the machine;

Fig. 5 is an elevation of the opposite end of the machine;

Fig. 6 is an enlarged transverse sectional elevation taken on the line 6—6 of Fig. 2;

Fig. 7 is a rear elevation of the mechanism shown in Fig. 6;

Fig. 8 is a side elevation of one of the bobbin carriers and the stop motion trip lever;

Fig. 9 is a plan view of the mechanism shown in Fig. 8.

In view of the fact that no invention resides in the braiding units per se, and that the operation of such braiding units is well known to those familiar with the art, my description thereof will be general.

Each braiding unit comprises a base plate A and a superposed bobbin platform B spaced apart from but rigidly attached to said base plate. In the bobbin platform B is formed a circuitous and intertwining raceway or slot b. Bobbin carriers C are slidably mounted on the platform B and have projections c which extend through the slot b to be engaged successively by a lug d on each gear of a train of gears D, which moves the bobbin carriers along the circuitous path b to effect the braiding operation.

Bobbins E are rotatably mounted on the respective bobbin carriers C, and a braiding thread e is led from each bobbin through suitable thread guides, and supports a stop motion operating element or weight F, which is vertically and slidably mounted on each bobbin carrier C. The threads are then led to a braiding mandrel G, where the braiding operation is effected. From the mandrel G the finished braid is passed through take-up rolls h which are rotatably mounted in a

take-up head or frame H. The rolls h are driven from a shaft I. From the take-up head H the braid is led to a take-off reel J, which is driven from the shaft I through the medium of a belt K.

The mechanism above described is common in braiding machines, and my invention consists in the consolidation of a plurality of these braiding units into one machine. For this purpose I provide a main frame consisting of a pair of longitudinally extending members 1 and 1^a spaced apart at one end by a transverse member 2. The base plates A, A of the series of braiding units are secured to each of the longitudinal frame members 1, 1^a, by means of bolts 3, 3. Secured to, and at intervals along, the frame member 1^a are bearings 4, 4, in which is rotatably mounted a main shaft 5. One extreme end 20 of the shaft 5 is mounted in a bracket 2^a formed integral with the transverse spacing member 2.

Adjacent each of the bearings 4, a spur gear 6 is secured to the shaft 5 and meshes with a spur gear 7 which is rotatably mounted on a stud 8 secured in one leg 9 of a bracket 10. The brackets 10 are each secured to one of the base plates A of a braiding unit, and provides bearings 11 and 12 for a short upright shaft 13. On each shaft 13, adjacent the bearing 11, is loosely and rotatably mounted a bevel gear 14 which meshes with a bevel gear 15 formed on one side of the said spur gear 7. Above the bearing 11 a spur gear 16 is secured to the shaft 13, and meshes with one of the gears of the gear train D of the respective braiding unit. Clutch teeth 17 are formed on the under side of the gear 14, which are adapted to be engaged by clutch teeth 18 formed on a collar 19 splined to the shaft 13.

Each clutch collar 19 is controlled by a lever 20 which loosely fits around the respective vertical shaft 13 and has a tail 21, loosely fitting within an aperture 22 formed in the bracket 10 which acts as a fulcrum for the lever 20 and prevents its rotation around the shaft 13. A vertically extending link 23 is pivotally attached at 24 to the lever 20, and extends through an aperture formed in an arm 25 attached to the under side of the bobbin platform B of each braiding unit. Above the arm 25, each link 23 is provided with a notch 26 into which a retaining latch 27 is adapted to enter and hold the teeth of the clutch collar 19 in engagement with the clutch teeth on the gear 14, thus the gear train D is set in motion.

Each retaining latch 27 is secured to a vertical shaft 28, the lower end of which is rotatably mounted in the bobbin platform B. An arm 29 is integrally formed on each retaining latch 27, and is operatively connected by a link 30 with a stop motion trip latch 31 pivoted at 32 to the top of the bobbin

table B. The stop motion trip latch 31 has a finger 33 which lies in the path of and is adapted to be engaged by the stop motion weight F when a thread e breaks and permits the weight to fall.

On the end of the main drive shaft 5, adjacent the bracket 2^a, is loosely mounted a driving pulley 35 having one half 36 of a clutch of any desired type thereon. The second half 37 of this clutch member is splined to the shaft 5, and is under direct control of a lever 38 which is pivoted at 39 to a bracket 40 secured to the spacing bar 2. The bracket 40 has an extension 41 provided with a flange having notches 42 and 43 formed therein for the reception of one end of a resilient locking element 44 which is secured at its opposite end to the clutch operating lever 38.

Standards 45, 45 are secured to and extend vertically from the lower main frame of the machine and the oppositely disposed pairs of standards are connected at their upper ends by transverse members 46, 46 and 46^a. A longitudinally extending bar 50 is secured to these transverse members and, together with said transverse members, acts as an upper or supplemental frame for the support of the take-up heads H and the take-off reels J.

The take-up heads H are secured directly to the longitudinal upper-frame member 50. The take-off reels J are rotatably mounted in elongated bearing brackets 49, 49 secured to the frame member 50.

Bearings, 51, 51 are secured to the said upper-frame member 50 and rotatably support a longitudinal shaft 52 which is provided with gears 53, 53 loosely mounted on and slidably movable with respect to the shaft 52. The gears 53 each mesh with and drive a gear 54 which is secured to the shaft I of each take-up head H. Each gear 53 is formed on one end of a sleeve 55, on the opposite end of which is formed a flange 56 having clutch teeth 57, adapted to engage similar clutch teeth 58 formed on a collar 59 secured to the shaft 52, thus the gears 53 are driven. A ratchet wheel 60 is also formed on the sleeve 55 with which a resilient pawl 61, secured to the upper frame member 50, cooperates.

The upper end of each of the vertical shafts 28 is journaled in a bearing 62 secured to the upper-frame member 50. Above the bearing 62 a yoke lever 63 is secured to each shaft 28, the forked end of which has projections 64 thereon which enter a groove 65 formed on the sleeve 55 between the flange 56 and the ratchet wheel 60 thereof. A spring 66 has one of its ends secured to the lever 63, and its opposite end secured to a post 67 projecting vertically from the upper-frame member 50, and tends to maintain the clutch teeth 57 of the sleeve 55 in engagement

with the clutch teeth 58 of the collar 59 on the shaft 52.

The shaft 52 is driven from the main shaft 5 by means of a bevel gear 68, secured to the shaft 5, which meshes with a bevel gear 69 secured to the lower end of a vertical shaft 70. The lower end of the shaft 70 is journaled in the transverse member 2 of the lower frame, and the upper end of said shaft is journaled in the transverse member 46^a of the upper frame. A bracket 71 is secured to one of the end upright standards 45 and has a bearing 72 surrounding the vertical shaft 70. Between this bearing 72 and the transverse member 46^a, a worm 73 is secured to the vertical shaft 70 which meshes with a worm wheel 74 secured to a short shaft 75. The shaft 75 is journaled in bearing 76 formed on the bracket 71, and has a gear 77 secured to one of its ends which meshes with a gear 78 secured to one end of the take-up shaft 52.

In operation, power is applied to the pulley 35 which through the clutch 36-37 drives the main shaft 5. The take-up shaft 52 is driven from the main shaft 5 in the manner above noted, thus the two longitudinal shafts of the machine are adapted to be continuously rotated, while the clutch parts 36-37 remains in cooperative engagement one with the other. Obviously by disengaging these clutch elements the entire consolidated machine may be stopped.

The bobbins of each individual braiding unit are carried around the circuitous path of the respective units by the gears of the gear train D, which are driven from the shaft 13 by the clutch collar 19 thereon. By disengaging the teeth of this clutch from those on the gear 14 the gear train D is brought to rest, but to effect this disengagement the link 23 must be released from the latch 27. To effect this release the said latch 27 must be rotated, thus the shaft 28 is rotated and by so doing the clutch teeth 57 of the take-up sleeve 55 are released from the teeth 58 of the clutch collar 59 on the take-up shaft 52, thus the take-up rolls h are brought to rest, and to maintain the tension on the finished braid between the take-up rolls h and the braiding mandrel G the pawl 61 functions to prevent back lash of the take-up sleeve 55.

Thus it will be seen that each unit may be operated or stopped independently of any and all of the other units, and adjustment, change of work, or any other necessary operations to be performed on one unit may be executed without interfering with the other units, all of which can be forming different kinds of braids at the same time. It, therefore, follows that the independent utility features of each unit remain intact while a plurality of units are consolidated into one machine having single driving mechanism

and occupying a minimum of floor space for a given number of units.

While I have illustrated a consolidated machine comprising four units, obviously such a machine consisting of two or more units would be within the scope of my invention.

In the drawing I have illustrated the main supporting frame 1 as having long legs 1^b which raises the braiding units to a position wherein the operator can conveniently adjust and otherwise attend to the braiding units and the other elements of the consolidated machine, thus eliminating the cost of erecting the common wooden elevated platforms generally constructed and employed for elevating the single unit braiding machines now in general use; these single machines being provided with short legs which raise the bobbin platform above the floor or wooden platform only a sufficient distance to provide working clearance for the elements of the machine, which lie below the said bobbin platform. I thereby attain a considerable saving in the cost of installation where a number of braiding units is to be employed.

I claim:

1. In a braiding machine the combination of a frame; a plurality of independent braiding units, each of which comprises thread manipulating mechanism mounted on said frame and take-up mechanism mounted on said frame above said thread manipulating mechanism; a power delivering element operatively mounted on the lower portion of said frame for operating the thread manipulating mechanism of the plurality of braiding units; a power delivering element operatively mounted on the upper portion of said frame and adapted to operate the take-up mechanisms of said braiding units; means for operatively connecting said power delivering elements; a single operating mechanism for driving said power delivering elements; an individual power controlling mechanism for each thread manipulating mechanism; an individual power controlling mechanism for each take-up mechanism; means for synchronously operating the power control mechanisms of the thread manipulating mechanism and the take-up mechanism of each independent braiding unit; and means for preventing back lash in said take-up mechanism upon operation of the power controlling mechanism thereof.

2. In a braiding machine, the combination of a main frame and a superposed supplementary frame, a series of braiding units each comprising a thread manipulating mechanism removably secured to said main frame and including a train of bobbin operating gears, and a take-up mechanism removably secured to said supplementary frame and having a main operating gear, a main shaft rotatably mounted in the main frame,

a short shaft for each thread manipulating mechanism operatively connected to the bobbin gear train thereof, mechanism including a clutch for operatively connecting said short shaft with the said main shaft, a latch controlling said clutch, a control shaft extending between said main and supplementary frames on which said latch is secured, an upper shaft rotatably mounted on said supplementary frame and operatively connected to said main shaft, a series of pinions loosely mounted on said upper shaft and respectively meshing with the operating gears of said take-up mechanisms, a clutch for operatively connecting each pinion to said upper shaft, and a pinion clutch operating lever secured to said control shaft, whereby rotation of the control shaft of any individual braiding unit will effect operation of the thread manipulating and take up clutches of said unit.

3. In a braiding machine, the combination of a main frame and a superposed supplementary frame, a series of braiding units each comprising a thread manipulating mechanism removably secured to said main frame and including a train of bobbin operating gears, and a take up mechanism removably secured to said supplementary frame and having a main operating gear, a main shaft rotatably mounted in the main frame, a short shaft for each thread manipulating mechanism operatively connected to the bobbin gear train thereof, mechanism including a clutch for operatively connecting said short shaft with the said main shaft, a latch controlling said clutch, a control shaft extending between said main and supplementary frames on which said latch is secured, an upper shaft rotatably mounted on said supplementary frame and operatively connected to said main shaft, a series of pinions loosely mounted on said upper shaft and respectively meshing with the operating gears of said take-up mechanisms, a clutch for operatively connecting each pinion to said upper shaft, a pinion clutch operating lever secured to said control shaft, whereby rotation of the control shaft of any individual braiding unit will effect operation of the thread manipulating and take up clutches of said unit, and means associated with each bobbin for operating said control shaft when the thread carried by said bobbin breaks or becomes slack, to disengage said clutches.

4. In a braiding machine, the combination of a main frame and a superposed supplementary frame, a series of braiding units each comprising a thread manipulating mechanism removably secured to said main frame and including a train of bobbin operating gears, and a take up mechanism removably secured to said supplementary frame and having a main operating gear, a main shaft rotatably mounted in the main frame, a short shaft for each thread manipu-

lating mechanism operatively connected to the bobbin gear train thereof, mechanism including a clutch for operatively connecting said short shaft with the said main shaft, a latch controlling said clutch, a control shaft extending between said main and supplementary frames on which said latch is secured, an upper shaft rotatably mounted on said supplementary frame and operatively connected to said main shaft, a series of pinions loosely mounted on said upper shaft and respectively meshing with the operating gears of said take up mechanisms, a clutch for operatively connecting each pinion to said upper shaft, a pinion clutch operating lever secured to said control shaft, whereby rotation of the control shaft of any individual braiding unit will effect operation of the thread manipulating and take up clutches of said unit, and means for preventing back lash of said take up operating pinion when said pinion is disconnected from said upper shaft.
